CLAIM

The ornamental design for an electronic module retainer, as shown and described.

DESCRIPTION

FIG. 1 is a top, front and side perspective view of an electronic module retainer showing my new design;

FIG. 2 is a right side elevation view thereof, the left side elevation view is identical thereto;

FIG. 3 is a front elevation view thereof;

FIG. 4 is a top plan view thereof;

FIG. 5 is a top, rear and side perspective view of one portion of the claimed design, on an enlarged scale; and,

FIG. 6 is a rear elevation view of one portion of the claimed design as illustrated in FIG. 5.

The broken line showing of the environment is for illustrative purposes only and forms no part of the claimed design.

1 Claim, 6 Drawing Sheets
